UNITED STATES PATENT OFFICE.

HOWARD P. STURGES, OF GLENELLYN, ILLINOIS.

GARAGE.

Application filed October 30, 1920. Serial No. 420,647.

To all whom it may concern:

Be it known that I, HOWARD P. STURGES, a citizen of the United States, residing at Glenellyn, in the county of Du Page and State 5 of Illinois, have invented certain new and useful Improvements in Garages, of which the following is a specification.

My invention relates to garages, and has particular reference to a garage having superposed floors to which the machine is 10 driven under its own power.

The principal object of the invention is to provide an improved building of the class described, for the storage of vehicles.

15 In the drawings illustrating a preferred embodiment of my invention—

Fig. 1 is a plan view of the ground floor of such an improved building;

Fig. 2 is a plan view of an intermediate 20 floor; and

Fig. 3 is an elevation of the building, partially in section.

I am aware that buildings have been proposed in which the various floors were intended to be connected by inclines or ramps 25 for the purpose of enabling self-propelled vehicles to be driven by their own power from one floor to another, without the use of elevators. However, so far as I am aware, such proposed structures have not found 30 favor in practice, for a number of reasons, the principal reason being the difficulty of manipulating the vehicle and the danger of accidents. My invention is designed to reduce 35 the difficulties and dangers of operation to a minimum.

Referring to the drawings, it will be seen that my improved building is of what may be termed the spiral type and is substantially circular. In Fig. 1, which is a ground 40 floor plan, it will be seen that one of the quadrants of the circle representing the outline of the building is replaced by a square, the square corner thus formed being utilized 45 for a passenger entrance 10 and a bank of elevators 11. It will be understood also that if ground space is very valuable, the lower floors of the building may also be made with corners so as to provide space for stores, 50 restaurants, or other commercial purposes.

Considering the building in its simplest form, that is to say, circular, it will be seen that the building, so far as its structural elements are concerned, is of skeleton type.

The columns 12 stand upon concrete bases 55 or piers 13 and preferably are constructed of reinforced concrete. Said columns at the center of the building are arranged in a circle 14 and surround a central well 15 which extends from the ground floor upwardly 60 through the middle of the building, the top of said well being covered by a conical skylight 16. The top of said sky-light 16 may be equipped with a ventilating hood 17 for drawing off any noxious vapors which may 65 be generated in the building, by reason of its use for the purpose described.

The ground floor area of the central well 15 may be used as a workshop where vehicles 70 can be cleaned or repaired.

The several floors of the building are inclined and arranged helically or spirally around the central well 15. They are, however, horizontal as to points on said floors on the same radial line; that is to say, the floor 75 extends laterally in a horizontal direction between the inner series of columns 14 and the outer series of columns 18 at the exterior of the building.

I have discovered that in order to make a 80 successful building of this type, it is necessary that there shall be substantially an uninterrupted roadway or driveway which is of sufficient width to enable vehicles to pass each other while driving at fair speed. Also, 85 in order to avoid great loss of space, the building should be of considerable size. A diameter in excess of two hundred feet is indicated for a building designed for the storage of passenger automobiles. This enables 90 me to accommodate a double row of parking spaces, comprising an outer row 19 and an inner row 20 on opposite sides of the double driveway 21, said driveway 21 being of ample width to enable the cars to pass 95 each other in ascending and descending the incline.

The large size of the building also enables the several floors to be made with substantial head-room, for instance, twelve to 100 fifteen feet in height, while at the same time the incline is kept down within very moderate limits. I find it advisable to mark the driveway with a central marker 22 which extends the entire length of the driveway 105 and divides the streams of ascending and descending cars. Under ordinary circumstances, the outer portion 23 of the driveway

will be used for ascending cars and the inner portion 24 of the driveway will be used for descending vehicles.

The entrance 25 and exit 26 for vehicles are preferably placed side by side on that side of the building where there is least pedestrian traffic, the entrance 10 for passengers being usually located on the busiest side of the building. In order to prevent the dangers incident to vehicles bucking the traffic in traveling to and from their parking places, it is desirable to have at some point on each floor a turning space, and to require all drivers to turn in this space when changing from the outer or up-driveway to the inner or down-driveway. It will be noted that there will be no occasion for vehicles to change from the down to the up-driveway, unless they overshoot their parking places by mistake. It will be understood that under ordinary circumstances, the outer row of parking places on the bottom floor will first be filled, after which the inner row will be filled up, a suitable check system being installed at the entrance to prevent confusion and theft.

It will be observed that the corner of the building furnishes ample room 27 for turning purposes, as above described, and also enables a car to withdraw out of the traffic when desired for any reason; for instance, if its assigned parking place is unlawfully appropriated by another vehicle.

Under ordinary circumstances it will be found that a building of this character may be constructed with as many as six floors. If desired, the lower portion of the building can be made strong enough so that at a later date, the structure may be extended upwardly, the upper floors being used for loft purposes.

In order to permit ready escape of exhaust vapors or other noxious gases, the inner enclosure which surrounds the central well 15 is preferably left open; that is to say, un-

glazed, there being provided merely a wall or parapet 28 to prevent vehicles or other objects from falling into the well.

I claim as my invention:

1. A building comprising an outer wall, 50 a helical floorway supported at its outer edge by said wall, a central well formed within the convolutions of said floorway and extending substantially from the bottom to the top of said building, and a series of 55 spaced columns along the inner edge of said floorway forming the sole connection between the convolutions of the floorway at said edge to permit substantially unobstructed circulation of air throughout the 60 building and from the space between the convolutions into the well.

2. A building comprising an outer wall, 65 a helical floorway supported at its outer edge by said wall, a central well formed within the convolutions of said floorway and extending substantially from the bottom to the top of said building, and a skeleton inner wall forming the support for the inner edge of said floorway to permit substantially unobstructed circulation of air 70 throughout the building and from the space between the convolutions into the well.

3. A building comprising an outer wall, 75 a helical floorway supported at its outer edge by said wall, a central well formed within the convolutions of said floorway and extending substantially from the bottom to the top of said building, supporting columns disposed at intervals along the inner edge of said floorway and forming the sole connection between the convolutions of the floorway at said edge to permit substantially unobstructed circulation of air 80 throughout the building and from the space 85 between the convolutions into the well, and a parapet extending along said inner edge and connecting said columns.

HOWARD P. STURGES.
